US00D868236S

(12) **United States Design Patent** (10) **Patent No.:** **US D868,236 S**
Frampton et al. (45) **Date of Patent:** **** Nov. 26, 2019**

(54) **SMOKE EVACUATION DEVICE CONTROL PANEL**

(71) Applicant: **Megadyne Medical Products, Inc.**, Draper, UT (US)

(72) Inventors: **Chad S. Frampton**, American Fork, UT (US); **Steven D. Andrews**, West Jordan, UT (US)

(73) Assignee: **Megadyne Medical Products, Inc.**, Draper, UT (US)

(**) Term: **15 Years**

(21) Appl. No.: **29/627,786**

(22) Filed: **Nov. 29, 2017**

(51) LOC (12) Cl. **24-01**

(52) U.S. Cl.

USPC **D24/107**; D24/144

(57) **CLAIM**

The ornamental design for a smoke evacuation device control panel, as shown and described.

DESCRIPTION

FIG. 1 is a perspective view of a smoke evacuation device control panel showing the new design; and, FIG. 2 is a front view thereof.

The broken lines illustrate portions of the smoke evacuation device that form no part of the claimed design.

1 Claim, 2 Drawing Sheets
